HUMIDIFYING SYSTEM

George L. Miner, Warwick, and Arthur Magson, Cumberland, R.I., assignors to Grinnell Corporation, Providence, R.I., a corporation of Delaware

Filed May 17, 1963, Ser. No. 281,203

9 Claims. (Cl. 236—44)

This invention relates to improvements in humidifying systems of the kind wherein the moisture is delivered into the atmosphere from atomizer nozzles which are supplied by air and water under pressure and which produce a finely divided water spray. Conventionally, such atomizers are located near the ceiling of an enclosure, and their spray is fine enough to evaporate before the droplets therein can reach objects in the enclosure, for example textile looms in a weave shed. Such machines must be run in an artificially high relative humidity, but they would be damaged or would produce inferior textiles if the droplets reached them before evaporating.

More particularly, this invention relates to improvements in humidifying systems employing atomizers of the kind in which the water and air under pressure are delivered to a "mixing" chamber in the atomizer adjacent the atomizer discharge orifice. The significance of this is that in such atomizers the water pressure in the system must exceed the air pressure as long as the water valve in each atomizer is open so that the air will not be forced back into the water system. These water valves are conventional in pressure atomizers and are essentially spring loaded relief valves which open and admit water to the mixing chamber when the water pressure reaches a predetermined value. There are no corresponding air valves in these atomizers so that air pressure led to the atomizers merely enters the mixing chamber and then escapes through the discharge orifice until the atomizer water valve opens, whereupon the mixture of air and water escapes from the orifice.

One feature of the present invention is that it provides a novel arrangement for maintaining the water pressure entering the nozzle mixing chamber at a higher value than the air pressure entering the mixing chamber as long as the atomizer water valves are open.

There are other types of atomizers in use today for which systems of a substantially different nature are required because they are of the "vacuum type" or "semi-pressure" type. In both these other types the water is discharged directly from the water system into atmosphere without first being discharged into a mixing chamber inside the atomizer. The air under pressure is also discharged directly to atmosphere, but closely adjacent to the water discharge and by this proximity the moving air educes the water stream and breaks it up. In such atomizers there is no danger that the air pressure can enter the water system and hence the air pressure often exceeds the water pressure.

Pressure type atomizers of the kind used with the present invention have certain advantages over the "vacuum" or "semi-pressure" atomizers. One such advantage is that they use appreciably less air for a given amount of water discharged, but where these pressure type atomizers have been used in the past difficulties have been encountered in satisfactorily relating the water and air pressures to keep the water pressure higher when the atomizer water valves are open. Further difficulties have been encountered in these earlier systems in relating the water and air pressures to maintain the optimum air-to-water ratio during the turning on, running, and shutting off of the atomizers.

With respect to this above-mentioned air-to-water ratio, the best quality water spray is achieved when the ratio of the cubic feet of air per hour to the pounds of water per hour delivered is in the neighborhood of 8:1. Values for

2

this ratio as low as 4:1 and as high as 12:1 can be tolerated, but when the ratio drops below 4:1 the spray becomes too coarse to evaporate quickly, and droplets fall on the surfaces in the enclosure being humidified. When the ratio exceeds 12:1 the spray quality does not suffer (nor is it significantly better than at 8:1) but the amount of air used is so great that there is a wasteful inefficiency. Another feature of the present invention is that it provides a novel arrangement for so relating the water and air pressures that the most advantageous air-to-water ratios are maintained, and this result is achieved with inexpensive equipment during the critical turning on and shutting off periods as well as during steady on conditions.

One of the characteristics of these systems is that they operate intermittently. Normally, the atomizers are turned off, but when the humidity detector senses that the relative humidity in the enclosure has fallen below the desired level it activates the system to turn on the atomizers. Between the time when the atomizers begin to discharge and the time when the atomizers are running at full capacity the spray discharge builds up from zero to full rate. This period of time is short, being in the order of a second or so, but even in this time it is important that the air-to-water ratio be within the desired limits and that the air pressure does not exceed the water pressure while the atomizer water valves are open. Similarly, when the humidity detector senses that the relative humidity in the enclosure has been restored to the desired level by the system operation it de-activates the system to turn off the atomizers, and again there is a short period of turning-off time during which the relative pressures of air and water must be controlled to assure that the air-to-water ratio is maintained and that the air pressure does not exceed the water pressure until the atomizer water valves are closed. The present invention provides a simple and inexpensive system for controlling these conditions during these initiating, running, and terminating periods.

In general, one system according to the present invention has a first valve which is located in the main air line from the air supply to the atomizers and which valve is opened by the humidity detector. A restriction associated with this first valve provides a pressure drop between the upstream and downstream sides. When the air pressure on the downstream side reaches a certain value it operates a second valve which is in a separate air line conducting air pressure from the air supply to the surface of water in a closed water supply tank. This air pressure on the water surface builds up the water pressure to the atomizers which receive water from the tank. The certain air pressure on the downstream side of the first valve and the other air pressure on the tank are related by the restriction so that the water pressure at the atomizers is higher than the air pressure at the atomizers when the water valves in the atomizers are open.

In general the proper air-to-water ratio is maintained by proper selection of the restriction which relates the air and water pressures, since the water pressure is derived from or controlled by the same pressurized air supply.

At the shut off, the system maintains the atomizer water pressure higher than the atomizer air pressure (at least until the atomizer water valve closes) by retarding the drop in air pressure in the water tank to make sure that the water pressure remains above the air pressure at the atomizer. The drop in air pressure in the tank results from the opening of a first exhaust port when the first valve is closed by the humidity detector. When the water pressure at the atomizer drops low enough to shut the water valve therein the air pressure on the downstream side of the first valve is low enough to rapidly exhaust the air pressure on the water tank through a second exhaust port. The drop in air pressure on the down-

stream side of the first valve results from the air escaping from the atomizers. During this shut-down, the proper air-to-water ratio is initially maintained by regulating the rate at which air escapes from the water tank via the first exhaust port relative to the rate at which air escapes from the atomizers and is later maintained by regulating the rate at which air pressure escapes from the water tank via the second exhaust port.

In this system being generally described some fixed pressure differential can be achieved by locating the water tank a certain distance above the level of the atomizers (which are usually all at about the same level). This "head" cannot be so great that it opens the water valves in the atomizers, but a significant amount of "head" makes possible the use of a larger restriction associated with the first valve.

It is an object of the present invention to provide an improved humidifying system for pressure-type atomizers in which the water pressure is maintained above the air pressure during discharge in a novel way and in which the air-to-water ratio is controlled in a novel way.

Another object of the invention is to provide a system in which the water pressure is at least in part derived from air imposed on a closed water tank, this air pressure coming from the same source which supplies air to the nozzles.

Another object is to provide a system of the kind described in which a restriction in the air supply line assists in maintaining the air pressure in the water tank at a higher level than the air pressure at the nozzles.

Another object is to provide a system of the kind described in which the actuation of a humidity detector admits supply air pressure to the actuator of a normally closed valve which when open admits air pressure to the nozzles from such supply.

Another object is to provide a system of the kind described in which nozzle air pressure of a certain amount closes a relatively large water tank air exhaust, whereby the air pressure in the tank quickly reaches full supply pressure.

Another object is the adjustment of these various components so that when the water pressure at the nozzles reaches a predetermined value it has already exceeded the air pressure in the nozzles.

Another object is to provide a relatively small water tank air exhaust which is opened when the new humidity condition causes the supply of air pressure to the tank to be stopped.

Another object is to provide an accelerator which causes the valve controlling air to the atomizers to close quickly when the humidity detector indicates the proper relative humidity has been achieved.

Another object is to provide a system of the kind described which is simple in construction, reliable in performance, easily installed and adjusted and convenient to maintain and repair.

Other objects will appear hereinafter.

The best mode in which it has been contemplated applying the principles of the present invention are shown in the accompanying drawings, but these are to be deemed primarily illustrative for it is intended that the patent shall cover by suitable expression in the claims whatever of patentable novelty exists in the invention disclosed.

In the drawings:

FIGURE 1 is a side-elevation view of one embodiment of the present invention with certain components shown in cross-section;

FIGURE 2 is an enlarged cross-sectioned side-elevation view of the discharge nozzle used in the system of FIGS. 1 and 4;

FIGURE 3 is an enlarged cross-sectioned side-elevation view of a valve controlling the large exhaust port for the water tank;

FIGURE 4 is a view like FIG. 1, but showing another embodiment of the invention;

FIGURE 5 is an enlarged cross-sectioned side-elevation view of another type of valve controlling the large exhaust for the water tank, and

FIGURE 6 is a fragmentary cross-sectioned side-elevation view of the orifice plate used in the system of FIG. 5.

Referring now to the embodiment of FIG. 1, the discharge nozzle 10 is one of many which are used in a system of this kind but which are not shown here because one such nozzle is sufficient to describe the operation of all. Air under pressure is brought to the nozzle by pipe 12 which connects to air manifold pipe 14. Water under pressure is brought to the nozzle 10 by pipe 16 which connects to water manifold 18.

FIGURE 2 shows how nozzle 10 is constructed. Water under pressure entering chamber 20 from pipe 16 acts on diaphragm 22 which is normally held in the position shown by compressed spring 24. The amount of spring compression is adjusted by nut 24 so that diaphragm 22 is not moved to the left by water pressure in chamber 20 until this pressure reaches a predetermined value, for example, 28 p.s.i. in a typical system. Above 28 p.s.i. the diaphragm movement moves cylinder 26 which is attached to the diaphragm at one end and which has a soft valve seating member 28 at the other end. This movement opens the valve aperture 30 which was closed by the seating member 28 and permits water from chamber 20 and pipe 16 to pass along passage 32 and through orifice 34 into intermediate chamber 36. This chamber 36 is also supplied with air under pressure which reaches it from pipe 12 via passages 38 and 40. Air and water are discharged from the intermediate chamber to atmosphere through the orifice 42.

From the foregoing it will be understood why pressure atomizers of this kind are subject to air entering the water system if the water valve 28-30 is open and if the air pressure in the intermediate chamber 36 exceeds the water pressure. In such case air can enter orifice 34 and pass along passage 32, through valve 28-30 (assumed to be open) and thus reach pipe 16. The disadvantage of air in the water system is that it forms an air cushion, and subsequent decreases in water manifold pressure during the atomizer shut-off result in large movements of water back into the water supply because of the expansion of the compressed air trapped in the water system. Such movements of large amounts of water may take so much time that the water pressure drops slowly at a time when more rapid pressure drops are desired.

Turning now to the operation of the rest of the system of FIG. 1, 44 designates generally a humidity detector of conventional design the construction of which is well-known to persons skilled in this art. It will suffice to explain that when the relative humidity in the enclosure served by the system fall below the desired level an electric signal is generated in leads 46 which connect to a solenoid operated three-way valve 48 in pipe 50. This signal opens this valve and allows air pressure from a main air supply pipe 52 to enter the actuator 54 via pipe 56 and also to enter pipe 58 through restriction 60.

The electric switch of the humidity detector 44 is operated by fluctuations in air pressure brought to the detector via pipes 62 and 64. More particularly, a humidity sensitive element in the detector varies the amount of opening of a bleed orifice in a first chamber supplied by pipe 62. The orifice opening is also effected by pressure in a second feed back chamber fed by pipe 64. The pressure fluctuations in the first chamber actuate the electric switch. The AMCO K-2 Control referred to at the end of the specification has such a construction.

Air pressure admitted to actuator 54 opens the valve 66 against the force of a spring 68 therein and permits supply air pressure in line 52 to enter the air manifold 14. A metering device in the form of an orifice plate 70 provides a pressure drop from the supply pressure to a lower value for the manifold 14. The pipe 52, plate 70 and valve 66 of FIG. 1 are the same in construction and

operation as the pipe 148, plate 156 and valve 122 of FIG. 6.

Air pressure admitted to pipe 58 passes through water trap 72 and is exhausted through port 74 in normally open auxiliary valve 76.

This valve 76 is held open by a spring 78 (see FIG. 3) which holds seating member 80 away from seat 82 and through cylinder 84 holds diaphragm 86 to the left against the force of much weaker spring 88. When air pressure in air manifold 14 reaches a certain level, for example about 20 p.s.i., it acts through pipe 90 on diaphragm 86 and overcomes the spring 78, thereby closing the seating member 80 on its seat 82. Thereafter air in pipe 92 cannot exhaust through port 74, and as a result pressure in water tank 94 builds up.

This tank is located with the water level therein about two feet above the level of the atomizer heads so that there is always a slight water pressure at these heads, even when there is no air pressure in the water tank 94. This head is not sufficient alone, however, to open the water valves 28-30 in the heads.

Water is supplied to the tank through a water supply line 96 and a float valve 98. The pressure in line 96 contributes to the pressure in the tank in the sense that the pressure in line 96 must be at least as great as the pressure in the tank 94, and operation of the float valve 98 in the tank effectively controls the introduction of water under pressure to the tank. A sight glass 100 is furnished so that the water level in the tank can be seen.

The water pressure thus derived builds up more rapidly in pipe 18 than the air pressure in air manifold 14 because of the fact that the orifice plate 70 produces a lower pressure in 14 than in 52, and even though a restriction 60 is between 52 and tank 94 the air volume of piping 50, 58, 92 and tank 94 is so much smaller than the air volume of manifold 14 that the pressure in tank 94 rises faster than the pressure in manifold 14, and exceeds the air pressure by the time the water pressure at the atomizer reaches 28 p.s.i. Another reason why the water pressure rises so much faster than the air pressure is that the water valves in each atomizer are closed, whereas the air reaching the atomizers can escape. This slows down the increase in air pressure at the atomizer.

Having achieved 28 p.s.i. the water pressure at the atomizer opens the water valves in the atomizers and the atomizers begin to discharge. In this initial period the water and air pressures continue to increase to their full operating values which in a typical system of the kind shown in FIG. 1 are approximately 32.5 p.s.i. and 30 p.s.i., respectively.

When the humidity detector 44 determines that the relative humidity has been restored to the desired level by the atomizer discharge it closes valve 48 which connects pipe 50 to an exhaust port 48a. As a result the air pressure in actuator 54 drops rapidly below the point where it overcomes spring 68, and valve 66 closes, shutting off air from the supply to manifold 14. This closing of valve 66 is accelerated in the embodiment of the drawings by the provision of an air chamber 102 under the diaphragm 104 in the actuator 54 and by a connection 106 from the air manifold 14 to the chamber 102. Since the pressure in air manifold 14 is quite high before valve 66 has closed some of this pressure in chamber 102 plus spring 68 causes the valve 66 to close much more quickly than it would with the spring alone when air is exhausted from upper chamber 108 of the actuator 54. A pressure reducing device 110 is located in line 106 to provide a pressure in chamber 102 which is less than the air manifold pressure.

As in the case of turning the atomizers on, it is desired during the turning off to maintain the water pressure at the atomizer higher than the air pressure there at least until the atomizer water valves close. This result is achieved in the embodiment of FIG. 1 because the exhaust port 48a provides the only escape for air pressure

on the tank 94 until valve 74 opens, and restriction 60 controls this exhausting. Valve 74 does not open until air pressure in manifold 14 drops to about 20 p.s.i. This latter drop results from the air in the manifold 14 escaping from each nozzle, and restriction 60 is set so that water pressure at atomizers does not fall below manifold (14) pressure at least until water pressure at atomizers is below 28 p.s.i. at which value water valves in atomizers close. Once these atomizer water valves all close both the air and water pressures can be lowered quickly in a convenient fashion, for example by having valve 76 open at 20 p.s.i. in manifold 14 and provide a larger (than restriction 60) exhaust for the air pressure in the tank. Pressure in manifold 14 will continue to drop by the exhausting of air through nozzle orifices 42.

Pressure guages 112 and 114 on the water line 18 and air manifold 14 respectively assist in the adjustment of the system to achieve the relative pressure values at the proper times as described.

FIGURE 4 shows another embodiment of the invention which is like that of FIG. 1 in all major respects, but in which the tank 116 initially receives air pressure from air manifold 118 and later exhausts to manifold 118 when valve 120 is closed. More particularly, opening valve 25 120 opens valve 122, and air pressure begins to build up in air manifold 118. This air pressure also begins to build up in tank 116 because auxiliary valve 123 is in the position shown in FIG. 5 until the air pressure in manifold 118 and line 124 reaches a certain value, for example 20 30 p.s.i. In position of valve 123 which is shown the air pressure from pipe 124 passes from chamber 126 along passage 128, through valve aperture 130, through passage 132 and out along pipe 134. The passage 128 is sufficiently restrictive so that when the pressure in pipe 35 124 reaches a predetermined value air cannot escape along the passage 128 fast enough and diaphragm 136 is moved downwardly against the force of spring 138 to close the soft seating member 140 on the aperture 130. Simultaneously, this movement of the diaphragm lowers seating 40 member 142 away from aperture 144 to open the same and connect pipe 146 with pipe 134.

Thus at the predetermined pressure in manifold 118 air pressure from the supply 148 is conducted to tank 116 via pipe 150, valve 120, pipe 152, restriction 154, pipe 146, 45 valve 123 and pipe 134. This predetermined pressure and the setting of valve 154 are selected so that when valve 123 operates as above described the air pressure in pipe 146 already exceeds the air pressure in the manifold 118 or at least exceeds this manifold pressure before the manifold pressure reaches the pressure of operation of the atomizer water valves.

Upon the closing of valve 120 to achieve a turning off of the atomizers 158, valve 122 closes and the manifold air pressure begins to drop. However, until this manifold air pressure reaches the operational value of valve 55 123 air in the tank 116 has to exhaust through ports 120a via restriction valve 154 which is set so that, even while dropping, the pressure in tank 116 is held above the air manifold pressure at least until the water pressure at the nozzles is below the value at which the water valves therein close. Water reaches the nozzles 158 through a pipe 160, water manifold pipe 162, and connecting pipes 164.

After the air pressure in manifold 118 drops to the predetermined value at which valve 123 operates, pipe 134 65 is again connected to pipe 124 and thereafter further venting of tank 116 is into the air manifold. In view of this it is preferred that the restriction valve 154 be set so that the pressure in 146 is somewhat higher than the pressure in 124 when the latter has dropped to the predetermined value.

One feature of the arrangement of FIG. 4 as thus described is that if during removal of the air pressure from tank 116 the air trapped in the water system (for example, at high points along with manifold 162) expands and drives water back along pipe 134 it might get into air

manifold 118 or air pipe 146. To prevent this the water trap 166 is used. In FIG. 1 such water can escape through exhaust port 74.

The humidity detector 163 in FIG. 4 is in all respects the same as the one shown in FIG. 1.

It will be understood that although only one atomizer head 10, 153 is shown in FIGS. 1 and 4, respectively, there would be many such heads in an actual system each connected to the water and air pipes in the same manner as those shown.

From the foregoing descriptions of the operations of the embodiments shown a person skilled in this art would be able to select components and adjust them without experimentation to obtain the operations described. However, as an aid to readers the components shown in FIG. 1 may be as follows: Pipe 52—1 inch; pipe 14—1 inch and reducing along its length; pipes 50, 56, 58, 92, 90, 106, 64, 62, 16, 12— $\frac{1}{4}$ inch; pipes 96, 18— $\frac{1}{2}$ inch; humidity detector 44—"AMCO K-2 Control" manufactured by American Moistening Company of Providence, Rhode Island; solenoid valve 48—"ASCO Three-Way Solenoid Valve," $\frac{1}{4}$ inch, made by Automatic Switch Co. of Floram Park, New Jersey; valve 66—"AMCO Two-Way Air Valve, Model C," $1\frac{1}{4}$ inches, manufactured by American Moistening Company of Providence, Rhode Island; orifice plate 70— $\frac{3}{8}$ inch; restriction 60— $\frac{1}{16}$ inch aperture adjustable; valve 76—"AMCO Monitor Valve," $\frac{1}{8}$ inch; atomizer 10—AMCO Aeromiser, 1960 style; water supply pressure—40-45 p.s.i.; air pressure supply—33 p.s.i.

What we claim is:

1. In combination with an atomizer nozzle having means for receiving a first fluid in gaseous state at a first pressure and a second fluid in liquid state at a second pressure which is higher than that of said first pressure, for mixing said gas and liquid together in said nozzle, and for discharging said fluids therefrom as a finely divided mist or spray, apparatus for controlling and correlating the pressures of said fluids in said nozzle, said apparatus comprising:

- (A) a source of said gas under pressure,
- (B) a source of said liquid,
- (C) first and second conduit means connecting said gas and liquid sources respectively to said atomizer nozzle receiving means,
- (D) third conduit means connecting said gas source to said liquid source,
- (E) flow control means, adapted to be activated by a humidity responsive means, for controlling the admission of said gas from said gas pressure source into said first and third conduit means,
- (F) auxiliary valve means in said third conduit means, operable in response to a predetermined value of pressure of said gas in said first conduit means for controlling the flow of said gas in said third conduit means to said liquid source,
- (G) flow restricting means between said gas pressure source and said first conduit for causing said first fluid to be delivered to said nozzle's first fluid receiving means at said first pressure and for establishing a pressure differential between said gas pressures in said first and third conduit means, and
- (H) flow restricting means in said third conduit means for controlling the rate of flow of said gas therethrough,

whereby gas upon being admitted into said first and third conduit means by said flow control means in response to a moisture requirement in the atmosphere controlled by said apparatus, flows through said first conduit means to said atomizer nozzle gas receiving means, and coincident therewith, flows through said third conduit means to said auxiliary valve means by which, upon the attainment of said predetermined pressure in said first conduit means, said gas is directed onto said liquid source to pressurize the same and cause said liquid to be delivered through

said second conduit means to said atomizer nozzle liquid receiving means at said second pressure.

2. In combination with an atomizer nozzle having a chamber for mixing a first fluid in gaseous state with a second fluid in liquid state, having means for receiving said gas at a first pressure, having separate means for receiving said liquid at a second pressure which is higher than said first pressure, and having means for discharging said fluids from said mixing chamber as a finely divided mist or spray, apparatus for controlling and correlating the pressures of said fluids in said nozzle, said apparatus comprising:

- (A) a source of said gas under pressure,
- (B) a source of said liquid,
- (C) first and second conduit means connecting said gas and liquid sources respectively to said atomizer nozzle receiving means,
- (D) third conduit means connecting said gas source to said liquid source,
- (E) flow control means, adapted to be activated by a humidity responsive means, for controlling the admission of said gas from said gas pressure source into said first and third conduit means,
- (F) auxiliary valve means in said conduit means, operable in response to a predetermined value of pressure of said gas in said first conduit means for controlling the flow of said gas in said third conduit means to said liquid source,
- (G) flow metering means between said gas pressure source and said first conduit means for reducing the pressure in said first conduit means substantially below the pressure of said gas pressure source, for causing said gas to be delivered to said gas receiving means at said first pressure and for establishing a pressure differential between said gas pressures in said first and third conduit means, respectively, and
- (H) adjustable flow metering means in said third conduit means for controlling the rate of flow of said gas therethrough in either direction,

40 whereby gas, upon being admitted into said first and third conduit means by said flow control means in response to a moisture requirement in the atmosphere controlled by said apparatus, flows at a reduced pressure through said first conduit means to said atomizer nozzle gas receiving means, and coincident therewith flows extending from said third conduit to said auxiliary valve means, at which, upon the attainment of said predetermined pressure in said first conduit means, said gas is admitted into said liquid source by said auxiliary valve means, thereby pressurizing said liquid source and causing said liquid to be delivered through said second conduit means to said atomizer nozzle liquid receiving means at said second pressure.

3. In combination with an atomizer nozzle having a chamber for mixing a first fluid in gaseous state with a second fluid in liquid state, having means for receiving said gas at a first pressure, having separate means for receiving said liquid at a second pressure which is higher than said first pressure, and having means for discharging said fluids from said mixing chamber as a finely divided mist or spray, apparatus for controlling and correlating the pressures of said fluids in said nozzle, said apparatus comprising:

- (A) a source of said gas under pressure,
- (B) a source of said liquid,
- (C) first and second conduit means connecting said gas and liquid sources respectively to said atomizer nozzle receiving means,
- (D) third conduit means connecting said gas source to said liquid source,
- (E) flow control means, adapted to be activated by a humidity responsive means, for controlling the admission of said gas from said gas pressure source into said first and third conduit means, said flow control means comprising:

- (1) a control valve in said first conduit means,
 (2) pilot valve in said third conduit means, and
 (3) humidity sensing means for sensing said fluctuations in relative humidity in said atmosphere and for controlling the operation of said control valve and pilot valve means in response to said fluctuations,
 (F) auxiliary valve means in said third conduit means, operable in response to a predetermined value of pressure of said gas in said first conduit means, for controlling the flow of said gas in said third conduit means to said liquid source,
 (G) an orifice between said gas pressure source and said first conduit means for reducing the pressure in said first conduit means from the gas source pressure to said first pressure, and for establishing a pressure differential between said gas and liquid pressures in said first and second conduit means respectively, and
 (H) adjustable flow metering means in said third conduit means for controlling the rate of flow of said gas therethrough in either direction,
 whereby gas, upon being admitted from said gas pressure source into said first and third conduit means by said control valve and said pilot valve means, respectively, in response to actuation of said humidity sensing means, flows through said first conduit means and arrives at said atomizer nozzle gas receiving means at said first pressure, and coincident therewith, flows through said third conduit means to said auxiliary valve means, where, upon the attainment of a minimum pressure in said first conduit means, it is admitted to said liquid source by said auxiliary valve means thereby pressurizing said liquid source and causing said liquid to be delivered through said second conduit means to said atomizer nozzle liquid receiving means at said second pressure.

4. In combination with an atomizer nozzle having a chamber for mixing a first fluid in gaseous state with a second fluid in liquid state, having means for receiving said gas at a first pressure, having means for receiving said liquid at a second pressure which is higher than said first pressure, and having means for discharging said fluids from said mixing chamber as a finely divided mist or spray, apparatus for controlling and correlating the pressures of said gas and liquid in said nozzle, said apparatus comprising:

- (A) a source of said gas under pressure,
- (B) a source of said liquid comprising a closed container partially filled with said liquid,
- (C) first and second conduit means connecting said gas and liquid sources respectively to said atomizer nozzle receiving means,
- (D) third conduit means connecting said gas source to said container,
- (E) flow control means, adapted to be activated by a humidity responsive means, for controlling the admission of said gas into said first and third conduit means, said flow control means comprising:

- (1) a control valve in said first conduit means having gas operated actuator which is connected to said third conduit means, which operates in response to a predetermined gas pressure in said third conduit means to open said control valve, and which operates in response to gas pressures below said predetermined pressure to close said control valve,
- (2) pilot valve means in said third conduit means for admitting said gas from said source into said third conduit means when said pilot valve means is in one position of movement and for blocking said admission and venting said third conduit means downstream from said pilot valve means when said pilot valve means is in another position of movement, and

- (3) humidity sensing means for sensing said fluctuations in relative humidity in said atmosphere and for controlling the position of movement of said pilot valve means in response thereto,
 (F) auxiliary valve means in said third conduit means between said liquid container and said control valve actuator connection and operable in response to a predetermined gas pressure in said first conduit means downstream side of said control valve, for controlling the admission of gas pressure to said liquid container,
 (G) means for establishing a pressure differential between said gas and liquid pressures in said first and second conduit means respectively, and
 (H) adjustable flow metering means in said third conduit means between said auxiliary valve means and said control valve actuator connection for controlling the rate of flow of said gas therethrough in either direction,
 20 whereby gas pressure from said gas pressure source, upon being admitted into said third conduit means by said pilot valve means in response to actuation of said humidity sensing means and subsequently into said first conduit means by said control valve in response to a predetermined value of pressure of said gas in said third conduit means, flows through said first conduit means to said atomizer nozzle gas receiving means, and coincident therewith, flows through said third conduit means at a controlled rate to said auxiliary valve means where, upon the attainment of a minimum pressure in said first conduit means, said gas is admitted to said liquid container by said auxiliary valve means, thereby pressurizing said liquid container and causing said liquid to be delivered through said second conduit means to said atomizer nozzle liquid receiving means at said second pressure.
5. The combination as recited in claim 4 wherein said liquid container comprises:
- (A) a sealed tank containing a quantity of liquid therein and having:
    - (1) a gas inlet to which said third conduit means is connected, and
    - (2) a liquid outlet to which said second conduit means is connected.
6. The combination as recited in claim 5 wherein said means for establishing said pressure differential between said gas and liquid pressures comprises means for so locating said tank relative to said atomizer that the liquid level in the tank is a predetermined distance above the level of said atomizer.
7. The combination as recited in claim 5 wherein said means for establishing said pressure differential between said gas and liquid pressure comprises a restriction in said first conduit means for reducing the pressure of said gas therein from the gas source pressure, whereby said first pressure has a value less than the pressure of said gas at said gas source.
8. The combination as recited in claim 4 wherein said control valve actuator has a piston-like member separating two actuator pressure chambers and is provided with means for accelerating the rate of closing of said control valve.
9. The combination as recited in claim 8 wherein said means for accelerating comprises a conduit connecting one of said actuator pressure chambers to said first conduit means at a point downstream of said control valve.
